UNITED STATES PATENT OFFICE.

GEORGE F. STEEDMAN, OF ST. LOUIS, MISSOURI.

FLUID-ACTUATED REGULATED CUSHIONED HOIST.

No. 845,827.

Specification of Letters Patent.

Patented March 5, 1907.

Application filed December 4, 1905. Serial No. 290,181.

To all whom it may concern.

Be it known that I, GEORGE F. STEEDMAN, a citizen of the United States, residing at St. Louis, Missouri, have invented a certain new and useful Improvement in Fluid-Actuated Regulated Cushioned Hoists, of which the following is a full, clear, and exact description, such as will enable others skilled in the art to which it appertains to make and use the same, reference being had to the accompanying drawings, forming part of this specification, in which—

Figure 1 is a diagrammatical view showing one arrangement of piping, cylinder, and operating-valve in which my invention is employed. Fig. 2 is a vertical longitudinal sectional view through a cylinder constructed in accordance with my invention. Fig. 3 is a fragmentary view, partly in section and partly in elevation, of a slightly-modified form of the piston-controlled grading device. Fig. 4 is a still further modified form of the grading device, and Fig. 5 is a modified form of a cylinder.

This invention relates to fluid-actuated hoists in which a cylinder is employed for containing a piston to be actuated by a suitable fluid, preferably air, one of the objects of the invention being to provide means whereby the speed of the stroke of the piston as it nears either end of the cylinder will be automatically reduced and cushioned in such a manner that all tendency to jar or unduly vibrate will be avoided. It is desirable to provide a cushion at each end of the cylinder when the piston is adjacent thereto, which cushion is due to the compression of the air existing between the end of the cylinder and the piston. If the exhaust is suddenly cut off, the piston will be brought to a sudden stop, and as a result thereof the load carried by said piston will receive a jar, which in some cases would be injurious to the load—as, for example, if glass is being raised or lowered by the piston. Aside from this the wear and tear on the hoist will be severe, and if the pressure is great enough the sudden compression of the air is liable to blow out the cylinder-head. To overcome the objections enumerated, I have provided an arrangement whereby the exhaust will be gradually but positively cut off, so that the volume of air existing between the end of the cylinder and the piston will be gradually diminished until the piston is brought to a position of rest.

As illustrating one form of mechanism whereby the objects of my invention may be carried out, 1 designates a cylinder, at the respective ends of which are the cylinder-heads 60 2 and 3. Each head is provided with a tube 4, comprising a socket-seat 4^a for the reception of hollow cut-offs 5, of which there is one on each side of the piston 6 operable in said cylinder. In the form illustrated in 65 Fig. 2 the cut-off is hollow and is provided with a series of perforations 7 in the form of a spiral, and as the piston moves toward the respective ends of the cylinder either of the cut-offs 5 will be introduced into its particular socket-seat 4^a. The recess formed by the tube 4 is in communication with an exhaust-pipe 8, communicating with the seat 4^a through the recess 9, and the cylinder receives its supply through a supply-pipe 10, 75 in communication with the cylinder through the recess 11.

It will be observed that the cylinder-heads are arranged so as to be interchangeable one for the other. The cylinder-head through 80 which the piston-stem projects is provided with a packing 12, held in place by a gland 13, while the head in the opposite end of the cylinder has its opening 14 closed by a plug 15, which plug may be interchanged for the 85 gland and packing in the opposite head, which gland and packing are in a recess corresponding to the opening 14.

The operation of the form illustrated in Figs. 1 and 2 may be described as follows: 90 The arrangement of piping is similar to that illustrated in my prior patent, No. 840,877, dated January 8, 1907, and shown in Fig. 1. The operating-valve 16 may be turned so as to exhaust the motive fluid from the pipe 17 95 in communication with the upper end of the cylinder and which is in communication with the regulating device 18. The regulating device 18 is preferably of the same construction as that shown in Fig. 5 of the drawings 100 of my patent referred to, so that a detailed description of same is not deemed necessary. The piston will be raised at the maximum speed until the hollow cut-off 5 begins to enter the socket-seat 4^a, through which the 105 fluid has been exhausting. As the end of the hollow cut-off 5 enters the socket-seat the exhaust will be initially cut off—that is to say, the fluid cannot exhaust through the socket-seat 4^a to the extent to which it previously exhausted, because the size of the opening will be decreased. In other words,

as soon as the end of the cut-off 5 enters the opening surrounded by the free end of the flange 4 the air will be permitted only to pass through the perforations 7. At first the air 5 may pass through all of the perforations; but as the cut-off continues to enter the socket-seat the perforations will successively become closed on account of the imperforate flange 4 until all of the perforations, or practically all of them, will be closed. It will be apparent that as the perforations successively close the volume of the exhaust will decrease, so that while a cushion is formed at the end of the cylinder the stopping of the 15 piston will be gradual and any tendency to unduly vibrate or jar will be avoided.

In order to illustrate one method of assembling the parts, I have shown the construction in Fig. 2 as including a piston-stem 20, 19, having a threaded end projecting through the respective cut-offs and through the piston. While this is an inexpensive and convenient manner of assembling the parts, I would have it understood that I do not wish 25 to limit myself to this exact arrangement, but reserve the right to employ other methods for accomplishing the same result.

In the form illustrated in Fig. 3 the flange 4 is substantially the same in construction as 30 the flange in Fig. 2. The cut-off, however, is tapered, said cut-off being designated by the reference-numeral 20, the taper thereof being toward the free end. Thus it will be seen that as the cut-off begins to enter the 35 socket-seat 4^a the opening will begin to be restricted until by the time the cut-off is in the position indicated in dotted lines the cylinder will have ceased to exhaust and the piston will be cushioned.

40 In Fig. 4 I have illustrated a still further modified form of cut-off, which is designated by the reference-numeral 21, and which consists of a hollow cylinder having a plurality of longitudinally-arranged slots 22 therein, 45 which slots are so arranged that as the cut-off moves into the socket-seat the slots will become less exposed, and thereby gradually cut off the exhaust in a manner similar to the operation described as applied to the construction shown in Fig. 2.

50 In Fig. 5 I have illustrated the cut-off as being on the outside of the cylinder at the end thereof, and it is obvious that this form may be employed without materially departing from the spirit of the invention. By so constructing the device that the cut-off is on the outside a saving of material is effected, because it will not require as much material to form the cylinder. Therefore I do not 55 limit my invention to a cut-off on the inside of the cylinder.

60 In describing the above invention I have referred to the cylinder as being of the "vertical" type, in which the piston has an 65 ascending and descending movement. How-

ever, I reserve the right to arrange the cylinder horizontally or at any other angle, and wherever the terms "vertical," "top," or "bottom," "ascending," or "descending" are employed I would have it understood 70 that they are not to be construed literally, but merely for the sake of distinguishing one movement from another.

Having thus described the invention, what is claimed as new, and desired to be secured 75 by Letters Patent, is—

1. In a device of the class described, the combination with a cylinder, of interchangeable cylinder-heads carried thereby, each cylinder-head having a central opening, inlet and outlet openings in the cylinder-heads, a piston in the cylinder, a piston-stem projecting through one of the central openings, a plug in the other cylinder-opening, and means carried by the piston for cutting off 85 communication between the outlet-openings and the cylinder; substantially as described.

2. In a device of the class described, the combination with a cylinder provided with heads having inlet and outlet openings, 90 flanges formed integral with the respective heads of the cylinder and forming socket-seats which communicate with the exhaust-openings in the heads of the cylinder, said flanges being spaced away from the side 95 walls of the cylinder, a piston in the cylinder, and hollow cut-offs carried by the piston and having openings in the walls thereof and insertable in the socket-seats whereby communication between the socket-seats and cylinder may be had only through the walls 100 of the cut-off; substantially as described.

3. In a device of the class described, the combination with a cylinder having inlet-openings, a hollow member at each end of the cylinder and communicating with an exhaust-opening in the end of the cylinder and spaced away from the side walls of the cylinder, a piston, concentric cut-offs carried by the piston and movable thereby into said 105 hollow members whereby communication may be cut off between the exhaust and the cylinder; substantially as described.

4. A device of the class described, comprising a cylinder having inlet and outlet 115 openings, a source of supply, tubes connected to the source of supply and to the inlet-openings, a piston operating in the cylinder, and an exhaust cut-off carried by the piston, in combination with means for controlling the 120 admission and exhaust of the motive fluid to and from the cylinder; substantially as described.

In testimony whereof I hereunto affix my signature, in the presence of two witnesses, 125 this 21st day of November, 1905.

GEORGE F. STEEDMAN.
